US0D1084633S

(12) **United States Design Patent** (10) **Patent No.:** **US D1,084,633 S**
(45) **Date of Patent:** **** Jul. 22, 2025**

(54) **INSOLE**

(71) Applicant: **Jiao Yang**, Shenzhen (CN)

(72) Inventor: **Jiao Yang**, Shenzhen (CN)

(**) Term: **15 Years**

(21) Appl. No.: **29/976,510**

(22) Filed: **Dec. 3, 2024**

(51) LOC (15) Cl. **02-04**

(52) U.S. Cl.

USPC **D2/961**
